LUMINAIRE

Russell A. Czellath, Brook Park, and Donald E. Husby,
Fairview Park, Ohio, assignors to Westinghouse Electric
Corporation

Filed Oct. 6, 1972, Ser. No. 295,618

Term of patent 14 years

Int. Cl. D26—03

U.S. Cl. D48—31

FIG. 1 is a perspective view of a luminaire showing our new design;

FIG. 2 is a top plan view thereof;

FIG. 3 is a front elevational view thereof;

FIG. 4 is a side elevational view thereof; and

FIG. 5 is a bottom plan view thereof.

The support is shown in broken lines in FIGS. 1 and 4, for illustrative purposes only and forms no part of this invention.

We claim:

The ornamental design for a luminaire, substantially as shown and described.
